DESIGN FOR A LIGHTING FIXTURE UNIT OR SIMILAR ARTICLE

Lemuel L. Stewart, Elkhart, Ind., assignor to
The Adlake Company, a corporation of Illinois

Application December 31, 1937, Serial No. 74,028

Term of patent 14 years

To all whom it may concern:

Be it known that I, Lemuel L. Stewart, a citizen of the United States of America and a resident of Elkhart, county of Elkhart, and State of Indiana, have invented a new, original, and ornamental Design for a Lighting Fixture Unit or Similar Article, of which the following is a specification, reference being had to the accompanying drawing, forming a part thereof, wherein

Fig. 1 is a perspective view of a lighting fixture unit or similar article showing my new design;

Fig. 2 is a fragmentary front elevational view of the units assembled;

Fig. 3 is a sectional view taken on the line 3—3 of Fig. 2.

The side panels 2 and 3 are light transmitting.
I claim:

The ornamental design for a lighting fixture unit or similar article, substantially as shown and described.

LEMUEL L. STEWART.
